CLAIM

The ornamental design for a shoe sole, as shown and described.

DESCRIPTION

FIG. 1 is a right side elevational view of a shoe sole showing our new design, the broken line showing of a shoe upper being environmental only and forms no part of the claimed design;

FIG. 2 is a bottom plan view thereof;

FIG. 3 is a left side elevational view thereof;

FIG. 4 is a top plan view thereof;

FIG. 5 is a front elevational view thereof;

FIG. 6 is a rear elevational view thereof.

FIG. 3

FIG. 4

FIG. 5

FIG. 6
